COTTON PICKING PROCESS

Edward L. Wilson, Jr., Baytown, Tex., assignor, by mesne assignments, to Esso Research and Engineering Company, Elizabeth, N.J., a corporation of Delaware
Filed Aug. 30, 1963, Ser. No. 305,659
9 Claims. (Cl. 56—41)

The present invention relates to a method of minimizing cavitomic degradation of cotton during the mechanical picking operation, and apparatus for carrying out that method. More particularly, the present invention relates to an apparatus and process for applying anticavítoma preservatives to seed cotton during the mechanical picking thereof, as set forth in detail hereinbelow.

The quality of mechanically picked cotton has been generally considered to be lower than that of hand-picked cotton. This partly due to the fact that the spindles of cotton picking machines become covered with dirt and resinous materials which are transferred to the cotton fibers, thereby staining them. In most modern machines, water is continuously applied to the spindles for the intended purpose of keeping them clean, but is only partly effective. In addition, the water further dampens the cotton which already may be moist due to rain or general ambient dampness. Moisture and warm temperatures promote cavitomic (microbial and fungal) degradation of the cotton. This degradation generally occurs during the initial storage period, before ginning and drying. Thus, it is very important that the cotton be protected from cavitomic degradation during the period between picking and drying. The present invention is directed toward providing such protection.

In the present invention, antimicrobial and/or fungicidal preservative materials (preferably in an oil carrier) are applied to the cotton during the mechanical picking operation, either by application to the spindles in place of the water-moistening step, or by spraying the preservative into the cotton-transport duct, or both. Where the preservative replaces the water as a spindle moistener, it has been found that the cotton is maintained cleaner and freer from stained fibers than had been the case when using water.

The preservative liquid of the present invention comprises a preservative compound in a carrier liquid, either with or without an emulsifying agent.

Suitable preservative compounds are 8-hydroxy quinoline, 2,4,6-trichlorophenol, 2-chloro-4-phenyl-phenol, 3, 5,3',4'-tetrachlorosalicylanilide, elemental sulfur, etc.

Suitable liquid carriers for the preservative materials are found in the various hydrocarbon streams. For application through the spindle, the carrier may suitably be Telura 35, a naphthenic hydrocarbon mixture boiling within the range of 550° F. to 700° F., and containing from 60% to 65% naphthenes, 25% to 30% aromatic hydrocarbons, and 5% to 10% paraffinic hydrocarbons. For spraying in the air duct, Solvesso 100 is exemplary of suitable carriers. This solvent boils within the range of 320° F. to 360° F., has an open cup flash point of 115° F. to 130° F., and has a viscosity of 0.77 centistoke at 25° C. It contains 97% aromatics, 0.5% naphthenes, and 2.5% paraffins. Other suitable liquid carriers are hexadecyl alcohol, isopropanol, and like compounds.

When the preservative liquid is to be applied by contact with the spindle, highly aromatic carrier oils should not be employed since the doffing members in mechanical pickers are constructed of rubber and may be degraded by highly aromatic hydrocarbons.

If desired, or if necessary, in order to form an emulsion of the preservative compound in the liquid carrier, an emulsifying agent such as xylene, alkyl aryl polyether

2

alcohol, polyethylene glycol oleate, etc., may be employed.

The concentration of the preservative material in the liquid carrier may vary widely, from about .01 weight percent to about 15 weight percent. A suitable concentration has been found to be about 3% to 6% by weight with respect to all of the above-mentioned preservative materials in the respective liquid carrier also above mentioned.

Where an emulsifier is desired, it may be used in suitable quantities, for example, about .01% to about 5%.

The rate of application of the preservative material in the liquid carrier is best measured by the amount of active ingredient per unit of cotton tested. It has been found with respect to all of the above-mentioned materials that positive results are obtained when the preservative is applied in amounts from about 0.4 to about 0.8 mg. per gram of cotton. In a gallons-per-bale range, this would represent about 0.5 to about 2.0 gallons of 2% solution per bale of cotton picked.

All of this may be better understood by reference to the drawing wherein:

FIG. 1 is a schematic drawing in partial section of a cotton picking apparatus in use, and

FIG. 2 is a representation of the construction of the cotton picking apparatus specifically showing the relationship between the spindles and the spindle moisteners.

Referring now to FIG. 1, a cotton picking apparatus generally indicated by the figure 100 is shown mounted upon a tractor unit 102, and is indicated as moving from the left to the right in order to remove cotton from the plant 103. The scoop means 104 embraces the cotton plants and guides them into contact with the spindles 105 whereby the cotton bolls are removed from the plants and are retained upon the spindles by means of barbs thereon.

The cotton on the barbed spindles is transported by rotation thereof into contact with the rotating doffers 106, whereby the cotton is removed from the spindle and falls to the floor of the picking mechanism 108. From thence the cotton is transported by way of an air stream within a duct 110, and is discharged into a basket means 112. The air stream is induced within the duct 110 by means of blower 114, which is driven by a power take-off from the tractor 102.

The cotton preservative fluid is introduced into the duct 110 by means of nozzle 120 and pump 122 from a storage tank 124. Alternatively, the tank 124 may be pressurized by the introduction of compressed air thereinto. It is preferred that the nozzle 120 be a pneumatic nozzle wherein the preservative liquid is injected into a high-velocity air stream. This provides excellent dispersion of the liquid droplets to form a fine mist. Suitably in conjunction with the addition of the preservative into the duct 110, the preservative is also added to spindle moisteners 126 by way of line 128.

Thus, by the practice of the present invention, the cotton is removed from the plant and is contacted immediately by the preservative oil which is carried by the spindle 105, and may be alternatively or further contacted with preservative oil within the duct 110 by means of the spray 120. Therefore, the cotton which is held in the basket 112 is protected as it is picked from cavitomic bio-degradation.

Referring now to FIG. 2, the operations of the spindles, spindle moisteners and doffers are more specifically illustrated. As the spindles 105 rotate from the right to the left, they are contacted by the doffers 106, which remove the cotton from the barbs on the spindle. The cotton-free spindles 105 are then contacted with the spindle moisteners 126, which are supplied with the preservative fluid by way of branches of line 128.

As exemplary of the practice of the present invention, a long staple cotton was picked under the following conditions.

EXAMPLE 1

A cotton field in the lower Rio Grande Valley was the subject of the experimental run. Early in the morning in July, when the moisture was fairly high, cotton was mechanically picked and 8-hydroxy quinoline fungicide was applied in Telura 35 or Solvesso 100 (see Table I for characteristics). Either of two methods was used: (1) application through the spindle, or (2) in the form of a mist in the conveying duct from the picker into the temporary storage hopper.

Samples of cotton were obtained and tested to determine the degree of cavitoma which had occurred. The method used was that set forth in the article by Charles M. Andrews and Lyle E. Hessler in "Textile Research Journal," vol. 32, No. 10, October 1962, pp. 862 through 864. In general, this test involves treating a one-half gram sample of cotton in a test tube with 10 ml. of a 0.1% solution of benzidine in 10% acetic acid. The sample is stirred with a glass stirring rod to facilitate absorption by the sample and the color is allowed to develop fully. This requires from 30 to 60 seconds, depending on the intensity of the color. A 10 by 70 mm. test tube is then filled with the solution and the intensity of the solution's color on a scale from 0 to 8 is observed through the depth of the tube and compared with colors on a standard chart. The color ranges from a pale yellow to a dark orange and begins fading in 4 to 5 minutes. The degree of biological damage is proportional to the intensity of the color.

The samples of cotton that were taken were submitted to the cavitoma test above described, and the results of these tests are set forth in Table I below.

I claim:

1. In the method of mechanically picking cotton wherein cotton bolls are removed from growing plants by moving barbed spindles and are removed from the spindles by doffers, said spindles being moistened to facilitate the picking and doffing operation, and said cotton is transported from said doffers to a basket by a stream of air, the improvement of contacting said cotton with a preservative during said mechanical picking.
2. A method in accordance with claim 1 wherein said contact is accomplished while said cotton is being transported by said stream of air.
3. A method in accordance with claim 1 wherein said preservative is applied to said spindles and thereby contacted with said cotton.
4. The method in accordance with claim 1 wherein said preservative is 8-hydroxy quinoline.
5. A method in accordance with claim 1 wherein said preservative is a 2% solution of 8-hydroxy quinoline in an oil solvent, and said preservative is applied in amounts within the range of 0.4 to 0.8 mg. per gram of cotton.
6. A method in accordance with claim 5 wherein said oil solvent boils within the range of 550° F. to 700° F. and contains from 60% to 65% naphthenes, 25% to 30% aromatics, and 5% to 10% paraffins.
7. In combination with a cotton picking device having spindles, doffers, a cotton transport duct, and blower means for moving cotton through said duct; means for introducing a preservative into said transport duct.
8. Apparatus in accordance with claim 7 wherein said introducing means comprises a preservative storage tank, spray means within said duct, and conduit means connecting said storage tank and said spray means.
9. Apparatus in accordance with claim 8 wherein said spray means includes means for pumping preservative

Table I

Treatment	Method of Application	Amount of Formulation Applied, Pints/Bale	Moisture Content of Cotton Picked, Wt. Percent	4 Days' Storage		8 Days' Storage		12 Days' Storage	
				Lint Grade ²	Cavitoma Rating ³	Lint Grade ²	Cavitoma Rating ³	Lint Grade ²	Cavitoma Rating ³
Check		None	13.7	LM	2	LM	2	LM	3
3% 8HQ ⁶ in Solvesso 100 ⁵	Mist ¹	3.14	11.9	SLM	2	SLM	1	SLM	1
4% 8HQ ⁶ in Telura 35 ⁴	Spindle	3.75	13.7	LM	2	LM ⁺	2-3	LM	2
6% 8HQ ⁶ in Solvesso 100 ⁵	Mist ¹	2.27	11.9	SLM	2	SLM ⁺	1	SLM	1
6% 8HQ ⁶ in Solvesso 100 ⁵	Mist ¹	3.87	13.2	SLM	1-2	SLM	1	SLM	1-2
10% 8HQ ⁶ in Solvesso 100 ⁵	Mist ¹	2.56	11.0	SLM	1	SLM	1	LM ⁺	1-2

¹ Mist application was made in the air conveyor duct of the picker.

² Lint grades are defined as follows in decreasing order: Good Middling (GM); Strick Middling (SM); Middling (M); Strict Low Middling (SLM); Low Middling (LM); Strict Good Ordinary (SGO); Good Ordinary (GO); Below Grade (BG).

³ Cavitoma Ledger: 0-1, No Cavitoma; 2-3, Borderline; Above 3, Cavitoma.

⁴ Telura 35 is a naphthenic oil boiling from 550-700° F., having a flash point of 300-310° F., and a viscosity of 56 SSU at 100° F. It contains 60-65% naphthenes, 25-30% aromatics, and 5-10% paraffins. It is marketed under the trade name "Enco" or "Esso Cotton Fiber Spray."

⁵ Solvesso 100 is an aromatic kerosene boiling from 320-360° F., having a flash (open cup) point of 115-130° F., and a viscosity of 0.77 cs at 25° C. It contains 97 aromatics, 0.5% naphthenes, and 2.5% paraffins. It is also marketed as "Enco Aromatic 100."

⁶ 8HQ is 8-hydroxy quinoline.

It will be seen from the table that application of 4% 8-hydroxy quinoline in Telura 35 through the spindle was the least effective method, but still yielded an advantage when compared with the control sample after 8 and 12 days storage.

The application of the hydroxy quinoline in the form of a mist was much more effective and protected the cotton from cavitomic degradation, even after 12 days storage.

Having disclosed the present invention in detail and having set forth a preferred embodiment thereof, as well as a preferred mode of practicing the process of the present invention, the Letters Patent should be restricted not by the specific examples herein given, but only by the appended claims.

from said storage tank, through said conduit means, and to said spray means.
